CLAIM

I claim the ornamental design for a bag, as shown and described.

DESCRIPTION

FIG. 1 is a perspective view of a bag showing my new design;

FIG. 2 is another perspective view of the bag of FIG. 1 shown in an open configuration;

FIG. 3 is a yet another perspective view of the bag of FIG. 1 shown in an open configuration, with the interior flap shown folded downward;

FIG. 4 is a top view of the bag as shown in FIG. 1;

FIG. 5 is a bottom view of the bag as shown in FIG. 1;

FIG. 6 is a front view of the bag as shown in FIG. 1;

FIG. 7 is a back view of the bag as shown in FIG. 1;

FIG. 8 is a left-side view of the bag as shown in FIG. 1; and,

FIG. 9 is a right-side view of the bag as shown in FIG. 1. The dash line shown in the drawing is showcasing stiches only and forms no part of the claimed design.
